Des. 214,514
Patented June 24, 1969

214,514

TOY ELEPHANT HEAD OR THE LIKE

Reuben B. Klamer, 9460 Wilshire Blvd., Beverly Hills, Calif. 90212, and Robert Y. Allen and Melvin Shaw, both of 2372 S. Veteran Ave., Los Angeles, Calif. 90064

Continuation-in-part of design application Ser. No. 7,790, July 13, 1967. This application May 3, 1968, Ser. No. 11,765

Term of patent 14 years

Int. Cl. D21—02

U.S. Cl. D34—2

FIG. 1

FIG. 3

FIG. 2

FIGURE 1 is a perspective view of a toy elephant head or the like embodying our ornamental design; FIGURE 2 is a right side view thereof; and, FIGURE 3 is a rear view thereof.

This application is a continuation-in-part of copending application Ser. No. D. 7,790, filed July 13, 1967, now abandoned.

We claim:

The ornamental design for a toy elephant head or the like, substantially as shown and described.
